UNITED STATES PATENT OFFICE

WILLIAM C. VAN VOORHIS, OF ANDREWS, SOUTH CAROLINA

RIM COMPRESSOR

Application filed February 25, 1929. Serial No. 342,499.

This invention relates to improvements in wheelwright machines and more particularly to a novel tool for compressing demountable rims such as are employed on pneumatic automobile wheels.

The principal object of this invention is to provide a rim compressor which in use will be convenient and positive acting.

Another important object of the invention is to provide a rim compressor which embodies a substantially wide compass of adjustment.

Another object of the invention is to provide a rim compressor having means whereby the operable parts thereof may be retained in rim compressing position.

Still another object of the invention is to provide a rim compressor which because of its simple construction can be manufactured at a cost within the economic demand of the public.

These and other objects of the invention will become more apparent to the reader after considering the invention as described and claimed hereinafter.

In the drawings:

Figure 1 represents a side elevation of a conventional rim showing the improved tool in the act of compressing the rim.

Figure 2 represents a side elevation through the improved device.

Figure 3 is a side elevation of the device in contracted position.

Figure 4 is a cross sectional view of the implement taken substantially on the line 4—4 of Figure 2 and looking in the direction of the arrows.

Figure 5 is a fragmentary detail sectional view of the tool.

Figure 6 is a perspective view of a detail of the construction.

Figure 7 is a detail sectional view of the tool.

Figure 8 is a fragmentary longitudinal sectional view of the tool.

Referring to the drawings wherein like numerals designate like parts, Figure 1 of the drawings shows a conventional pneumatic wheel rim which is generally referred to by A.

The improved tool includes a pair of slide sections 3 and 4. The section 3 has a flange 5 along one longitudinal edge portion thereof upon which the section 4 is adapted to ride. The section 3 has a longitudinally extending slot 6 and one edge portion of this slot is toothed to provide a rack 7. The outer end of each section is beveled and slotted transversely as at 8 to provide a hook 9. The inner end of the section 4 has a pin 10 disposed therethrough and through the slot 6 of the section 3. Pivottally mounted on this pin 10 is a U shaped pawl 11, the bight portion of which is adapted for engagement between the teeth of the rack 7. The inner end of the section 3 has a pin projection 12 for disposition through the slot 13 longitudinally formed in the section 4 and to the pin 12 is journaled the inner end of a lever which is generally referred to by numeral 14. This lever in construction consists of a pair of bars 15—15 which have their outer ends disposed laterally and secured together as at 16. Thus a space 17 is provided between the bars and this space is of sufficient extent to permit the reception of the section 3 when the tool is in the contracted position shown in Figure 3.

Each bar 15 of the lever 14 has a stud 18 at its outer side and adjacent the pivot pin 12 so for engagement between the teeth of the racks 19 on the pivotal arm 20, which arm is composed of a pair of straps 21—21 rigid at one end as at 22 and pivotally connected to the section 4 by a pin 23 adjacent the outer end of the section 4.

In use, the tool is applied to the rim so that the hooks 9 engage over the edges of the rim at diametrically opposite points. By moving the lever 14 in the direction of the arrow shown in Figure 2, the sections will fly together and in this movement will contract the rim. When rim has been contracted sufficiently, the bight portion of the pawl 11 may be engaged between certain teeth of the rack 7 for retaining the tool in contracted position. In order to accommodate the tool for various sized rims, it is only necessary that the proper adjustment of the arm 20 and the studs 18—18 be made.

Furthermore, the tool can be employed with equal satisfaction as an expander for rims by moving the lever 14 in the opposite direction after proper adjustment has been made.

5 Obviously certain changes in the specific shape, size, and materials may be resorted to in the construction of the novel tool without departing from the spirit and scope of the invention as claimed hereinafter.

10 Having thus described the invention, what I claim as new and desire to secure by Letters Patent is:—

15 1. A rim tool comprising a pair of slide sections, a lever pivotally connected at one end to one section, an arm pivotally connected at the outer end of the other section, adjustable connecting means between the arm and the lever, a hook at the outer end of each section, a rack and pawl fastener between said sections, said fastener consisting in providing a slot in one section, a rack at one edge of the slot, a connecting pin on the other section disposed through said slot, and a pawl carried by said last mentioned section for engagement with said rack.

20 2. A rim tool comprising a pair of slideable sections, a lever pivotally connected at one end to one section, an arm pivotally connected at the outer end of the other section, adjustable connecting means between the arm and the lever, a hook at the outer end of each section, a rack and pawl fastener between said sections, said fastener consisting in providing a slot in one section, a rack at one edge of the slot, a connecting pin on the other section disposed through said slot, and a pawl carried by said last mentioned section for engagement with the said rack, said pawl comprising a U-shaped member pivotally secured at its ends to the said section, the bight portion of said member being disposed through the slot for engagement with the said rack on the edge of the slot.

25 In testimony whereof I affix my signature.

45 WILLIAM C. VAN VOORHIS.
